DETACHABLE CLOSURE FOR CONTAINERS

Hubert Jezler, Zurich, Switzerland, assignor to
Kontroll A.-G., Zurich, Switzerland, a corpora-
tion of Switzerland

Application March 16, 1934, Serial No. 715,842
In Switzerland May 18, 1933

7 Claims. (Cl. 215—45)

The invention relates to a closure for containers provided with a mouth, spout and so forth, the invention relating particularly to closures wherein the closure parts can be detached completely from the container.

The object of the invention is to provide a closure of this type which can be closed and released easily and which, in spite of this, is pressed with a high pressure against the packing surface.

10 A further object resides therein that the closure part has such a shape that it bears snugly against the container walls and presents little obstruction to the application of tin caps or other packing material.

15 According to the invention these objects are obtained in that in a holder, containing the packing disc, which is fitted over the open end of the container for instance of the bottle or the like, is provided an open resilient spreading ring located 20 in inwardly open radial guides in the holder, and that means are also provided for pressing the open spreading ring against the walls of the bottle neck, and securing the ring in the locking position. As means for pressing the spreading ring 25 there are used, according to the invention, wedge surfaces which act on the free ends of the spreading ring. The spreading ring may thus, for example, be pressed against inclined walls of the neck so that when pressing the spreading ring together radially there is obtained simultaneously an axially directed pressure of the packing medium against the mouth of the bottle or the like.

The invention may be carried into effect in various ways. In all the forms of construction 35 however, the wedge action is obtained by a movable or rotary cap, sleeve, key or lever and thus the closure cover is pressed against the packing surface of the vessel.

40 In the accompanying drawings are illustrated a few examples of construction. In these drawings:

Fig. 1 is a longitudinal section of a bottle neck with the closure, whilst the closure parts on the left hand side are in the closed position and on 45 the right hand side directly before the parts enter into the locking position.

Fig. 2 is a side view of the closure cover with inserted spreading ring.

Fig. 3 shows a second form of construction 50 partly in side elevation, partly in section.

Fig. 4 is a section on the line IV—IV of Fig. 3.

Figs. 5, 6 and 7 show in side elevation, in axial section and in section on the line VII—VII of Fig. 6 a further form of construction of the 55 closure.

Fig. 8 shows in axial section a pot of glass, earthenware or the like with the new closure applied thereto.

Figs. 9 and 10 show a closure cover in section and in side elevation.

Fig. 11 shows a sheet metal can with the new closure.

Figs. 12, 13, 14 and 15 each show in section closure cap with a spreading ring guide.

In the construction shown in Figs. 1 and 2 the 10 vessel is in the form of a bottle which has a neck 1 provided with a radially outwardly extending projection 2 adjacent to the rim forming the mouth of the bottle. On the top of the rim rests the closure cover 3 with the soft disc-shaped 15 packing 4. The cover 3 is provided with a cylindrical skirt surrounding the projection 2. Near the lower end the cover 3 is provided with downwardly bent lugs 9. These lugs together form a guide for a spreading ring 8. The guide 20 is open radially inwards.

The distance between the lugs 9 is so selected that the spreading rings receive an efficient guide on all sides. The ring 8 is open, it consists of 25 springy material and tends to move away from the bottle neck 1 into the guide 7. In order to press the spreading ring against the projection 2 of the bottle neck 1 there is provided a cap 11 which is fitted over the closure cover 3. In the skirt of the cap 11 are provided ribs 13 which 30 become higher towards the upper end of the cap 11. The ribs 13 bear against the spreading ring 8 through the spaces 10. By axial movement of the cap 11 the ribs 13 press the spreading ring 8 against an inclined wall of the projection 2, whereby the packing 4 is pressed against the upper end face of the bottle neck 1. The lower end of the cap 11 is provided with an inwardly projecting flange 12 which when opening 35 the closure (Fig. 1 right hand half) bears against the lugs 9 and by means of which the closure cover 3, 4 is removed from the bottle.

In the form of construction in Figs. 3 and 4, the spreading ring 8 is located in a closed groove-shaped guide, open towards the inside of the closure cover 3. The cover skirt has a radial slot 17 through which the free ends of the spreading ring 8 pass radially to the outside. These ends are bent in the form of hooks 14. These hooks 45 project to the outside through an opening 15 in the cylindrical skirt of the cap 11. The longitudinal edges of the opening 15 are inclined and act as a wedge. When moving the cap 11 in an axial direction on the bottle neck 1 the hooks 14 of the spreading ring 8 are approached or 50 55

moved apart according to the direction of movement of the cap, whereby the spreading ring 8 either closed and pressed against the inclined surfaces of the projection 2 or removed from this.

- 5 For opening and closing the spreading ring 8 there may also be provided a separate key 15 as shown in Figs. 5 to 7. The spreading ring 8, located in a radial inwardly open guide 16 of the cover 3, is provided with hooked ends 18. 10 These hooks 18 project through the elliptical opening 19 of the key and rest in notches 20 thereof. By turning the key 15 from the middle position shown in Fig. 5 the hooks 18 pass out of the notches 20. The ring 8 can then expand. 15 The hooks 18 pass into the major diameter of the ellipse 19. The ring 8 then releases the enlargement 2 so that the cover can be removed.

The container (Fig. 8) to which the new closure is applied may be of any shape, for instance 20 the container may have an elliptical cross-section. The wall may be cylindrical or conical; it may be reduced at the upper end to form a neck and so on. The container and the cover may each consist of any suitable material such as sheet 25 metal glass, porcelain, earthenware, synthetic resin products, and so on.

With containers having elliptical cross-section the key is arranged at one end of the major axis. Any tubular body having an internal groove, a 30 spreading ring and a key may be used—the device forming an easily operated coupling for tubes, pipes and so on.

In the form of construction according to Figs. 9 and 10 end pieces 25, 26 of the clamping ring 8, 35 bent at an angle, project into an opening of a rotatably mounted key 28. By rocking the key 28 in the direction of the arrow the ends 25, 26 are pressed together by the wedge surfaces 27 and thus the ring 8 is pressed against the bottle 40 neck.

In Fig. 11 the container is shown as a sheet metal can 31, having a cylindrical outlet 30. To this the cover 3 is secured by means of a key 32 bent at an angle. The key 32 in this case 45 may be secured by a lead seal 33. The wedge action of the key 32 on the spreading ring 8 may in this construction be of the type shown in Figs. 9 and 10.

The guide for the spreading ring may be of 50 any suitable shape. It is important for the ring to have a free radial inward path and that in the direction of the bottle neck axis it lies with free play between rigid walls, tongues and so forth.

55 In Figs. 12 to 15 are shown by way of example a few guides. As shown in Fig. 12 a guide 35 for the spreading ring may be formed by bending or beading over the lower rim 36 of the skirt 60 of the cover 3. In this case the spreading ring forced radially inwards by wedge action may act against the annular surface 37.

As shown in Fig. 13 only a few tongues 38, instead of the entire ring, may be curled inwardly 65 and upwardly. The spreading ring located in the groove 35 thus lies on a number of pressure surfaces 39 of the lugs 38. For guiding the spreading ring tongues 41 may be stamped and project radially inward from the skirt 40 of the cover 70 3 as shown in Fig. 14. Further the lower rim of the skirt of the cover 3 is offset inwardly so that between the lower edges of the tongues 41 and the shoulder 42 there is formed a guide for the spreading ring 8.

75 Fig. 15 shows a further form of construction.

In this case wide tongues 45 are bent inwardly and downwardly from the skirt 44 of the cover 3. The lower edge 46 of the skirt 44 is bent inwardly and upwardly. The wall 47 of the bent over portion and the tongues 45 form a guide 5 for the spreading ring.

Instead of the stamped tongues there may be provided radial inwardly pressed projecting ribs, fins and so forth.

The cross section of the wire from which the spreading ring is formed may be square, rectangular or of any other shape.

To form a guide for the spreading ring ribs, recesses or merely points may be pressed into the cylindrical skirt of the cover when made of sheet metal, to form an abutment for the ring.

The closure may be constructed with a springy ring of which the configuration may be altered by suitable means to attach or detach the cover from the container.

What I wish to claim is:

1. A removable closure for bottles and other containers such as cans and so forth having an opening provided with a rim and a radially outwardly extending projection, said closure including a cover adapted to close said opening, an inwardly open guide on said cover, a split spring ring located in said guide and normally tending to open out so as to disengage itself from under said projection, and means associated with said ring and when moved relatively to the cover in one direction serving to close the ring around said opening under said projection and when moved in another direction serving to allow said ring to open out away from said projection. 30 35

2. A removable cover according to claim 1, wherein said guide comprises a plurality of spaced radial members bent inwardly.

3. A removable cover according to claim 1, wherein said guide consists of a plurality of 40 spaced radial inwardly open members and wherein said means comprise a cap mounted on said cover and capable of axial movement relatively to said cover, and ribs on said cap engaging said ring between said spaced members. 45

4. A removable cover according to claim 1, wherein said means comprise a member movable relatively to said cover, and wedge elements on said member and adapted to co-operate with said ring to cause it to contract around said rim 50 and to allow it to expand away from said rim in response to the movement of the member on which they are carried.

5. A removable cover adapted to close an opening, and including a skirt having a radial opening therein, an inwardly open guide at the lower end of said skirt, an open spring ring in said guide and having hooked ends projecting outwardly through said opening, an operating member pivotally mounted on said hooked ends, and having a pair of converging cam faces engaged by said hooked ends, the arrangement being such that when said member is swung in one direction the ring is contracted, whilst when said member 60 is swung away in the opposite direction, said ring is allowed to expand. 65

6. A removable cover according to claim 1, including a skirt on said cover, said skirt being curled inwardly at its lower end, and a plurality of inwardly bent tongues in said skirt above said curled-in portion, said curled-in portion and said tongues forming said guide. 70

7. A removable cover for containers having a rim encircling an opening and presenting a 75

projection having an inclined surface below the end of said rim, said cover comprising in combination a disc adapted to fit on said rim so as to close said opening, a packing member between said disc and said rim, a skirt on said cover, said skirt extending to below said rim, said skirt having an annular inwardly open recess at or near the lower end thereof, an expanding split ring

in said recess, and operating means associated with said ring and adapted, according to their movement to contract said ring against the inclined surface so as to draw said cover and said packing disc against said rim and to allow said ring to expand. 5
